214,572

CLIMBING LADDER OR SIMILAR ARTICLE

Irwin Cohn, 746 West St., Leominster, Mass. 01453

Filed Sept. 17, 1968, Ser. No. 13,570

Term of patent 3½ years

Int. Cl. D25—99

U.S. Cl. D34—5

FIG. 1 is a front elevational view of a climbing ladder or similar article embodying my new design;

FIG. 2 is a side elevational view thereof;

FIG. 3 is a bottom plan view thereof;

FIG. 4 is a cross-sectional view taken on line 4—4 of FIG. 1;

FIG. 5 is a cross-sectional view taken on line 5—5 of FIG. 1; and

FIG. 6 is a cross-sectional view taken on line 6—6 of FIG. 3.

The broken line portions in FIGS. 1 and 2 are to indicate indeterminate length.

I claim:

The ornamental design for a climbing ladder or similar article, substantially as shown and described.
